FREQUENCY MULTIPLIER

Application filed August 9, 1924, Serial No. 731,225, and in Germany August 17, 1923.

In the known methods for increasing the frequency of any fundamental period by means of static transformers a large number of frequency transformers connected in cascade was used, each step of the arrangement only doubling or tripling the frequency. This method has, however, a poor efficiency because every step of the cascade causes a loss of energy. This loss increases nearly in proportion to the frequency which, of course, rises in geometrical progression.

This method had, therefore, low efficiency and the arrangement was complicated and expensive. Accordingly this method was replaced by that of increasing the frequency by means of a single transformer. By this method it was possible to attain ratios of transformation as high as 1:27. In using one single transformer a very simple arrangement was obtained, but an analysis of the radiated oscillation showed that this oscillation contained very many adjacent harmonics. These harmonics of a transmitting station greatly disturb those neighboring receiving stations which are tuned to a wavelength which is by chance in accordance with one of these harmonics.

The present invention relates to an arrangement for frequently increase by which a final frequency is generated which contains only very few disturbing harmonics. According to the invention the frequency increase, particularly that of a high multiple of the fundamental frequency is always carried out by means of two transformers, the first fitted up for a great frequency increase and the second only for a small frequency increase, for instance doubling or tripling the input frequency.

It is attained by reason that the disturbing harmonics according to the invention greatly differ from the radiated desired final oscillation in spite of a very high transformation. By means of traps and filters, well known in the art these greatly differing harmonics can easily be eliminated.

The single figure shows diagrammatically an embodiment of my invention.

In said figure, the high frequency generator is shown coupled to the first frequency

changer circuit which in turn leads to the second frequency changer and then to the utilizing circuit.

An example will serve to explain this invention. Assume the fundamental frequency to be 10,000 and it is desired to increase it 27 times. The first transformation will then increase the fundamental frequency 9 times, that is, to 90,000 and the second transformation increases this frequency 3 times, that is, to 270,000. Thus the useful frequency is 270,000 while the next disturbing waves have the frequencies 450,000 and 90,000, assuming that the frequency multipliers used generate only odd harmonics. Many of the well known frequency changers can be made to generate only odd harmonics. These harmonics greatly differing from the useful frequency have but small energy and can if necessary be easily eliminated by means of any well known filtering circuits, as pointed out above.

The above described arrangement is specially simplified if, as in the above example, the second transformation increases the frequency 3 times and if the first transformation is so chosen that it increases the fundamental frequency by an odd but greater multiple. In this case the direct current magnetization absolutely necessary for the even multiples can be left out and an extraordinarily simple and good arrangement is obtained.

Having described my invention, I claim:

1. In a high frequency multiplication system of the character described for changing a fundamental frequency into a higher frequency comprising in combination an iron cored frequency multiplication transformer having its input circuit fed by current of said fundamental frequency, a second frequency multiplication transformer connected in cascade with said first frequency transformer and having a multiplication ratio relatively small with respect to that of the first frequency transformer.

2. In a high frequency multiplication system of the character described for changing a fundamental frequency into another higher frequency comprising in combination an iron-

- cored frequency transformer having its input circuit fed by said fundamental frequency, a second frequency transformer having a multiplication ratio relatively small with respect to that of the first frequency transformer and means for coupling the output circuit of the first transformer with said input circuit of said second transformer.
3. A device for greatly increasing the frequency of oscillation in an electrical system by means of static transformers which comprises a pair of static transformers, the second thereof being adapted to increase the output frequency of the first three times and the first thereof being adapted to increase the fundamental frequency by an odd but greater multiple, whereby it is unnecessary to magnetize the cores of the transformers by direct current.
- 10 4. A device for greatly increasing the frequency of electrical oscillations by means of static transformers which comprises means including a first static transformer adapted to increase the fundamental frequency by an odd multiple and a second static transformer adapted to increase the frequency produced by said first static transformer by a multiple less than the said multiple increase in said first transformation.
- 15 5. A device for greatly increasing the frequency of electrical oscillations by means of static transformers which comprises means including a first static transformer adapted to increase the fundamental frequency nine times and a second static transformer adapted to increase the frequency produced by said first static transformer three times.
